Warren LaFayette Fish,
BY Drake & Co., ATTYS.

UNITED STATES PATENT OFFICE.

WARREN LA FAYETTE FISH, OF NEWARK, NEW JERSEY.

LANTERN-SUPPORTING ARM FOR BICYCLES.

SPECIFICATION forming part of Letters Patent No. 356,112, dated January 18, 1887.

Application filed August 6, 1886. Serial No. 210,170. (No model.)

To all whom it may concern:

Be it known that I, WARREN LA FAYETTE FISH, a citizen of the United States, residing at Newark, in the county of Essex and State of New Jersey, have invented certain new and useful Improvements in Lantern-Supporting Arms for Bicycles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to enable the light of a bicycle-lantern to be readily directed to any desired point, to enable the lantern to be raised or lowered in its relation to the ground, to be transferred from one side of the 20 vehicle to the other without the use of duplicate supporting-arms, and to be removed from the bracket for purposes of cleaning, filling, &c.

25 The invention consists in the improved bicycle-lantern-supporting arm or bracket having the arrangements and combination of parts substantially as will be hereinafter set forth, and finally embodied in the clauses of the claim.

Referring to the accompanying drawings, 30 in which like letters indicate corresponding parts in each of the several figures, Figure 1 is a side elevation showing a bracket and adjustable supporting-arm secured to the fork of a bicycle. Fig. 2 is an edge view of said 35 bracket and a portion of said arm. Fig. 3 is a vertical and longitudinal section through the bracket, and Fig. 4 illustrates two constructions of a clip portion of the bracket.

In said drawings, *a* illustrates a portion of 40 an ordinary bicycle-fork, between the prongs of which the wheel is arranged. *b* is a bracket secured to said fork by means of a clip, *c*, having an adjustable relation to said bracket, so that the latter may be secured to either of 45 the prongs of the fork, on either side of the wheel, without changing the relation of the arm and bracket, by simply loosening the screw or nut *c'* and removing the bracket from the fork, then turning the clip in the perforation *b'* of 50 the bracket, and, finally, securing the arms to the opposite bracket. The bracket and clip may be integral under some conditions, but

not with the best results. The clip is provided with a bent end, *c''*, to extend around one edge of the fork; and at the opposite end is provided with a screw-shank, *c'*, to enter the perforation *b'* of the bracket and allow the bracket to be clamped to the fork.

The bracket is provided with recesses or grooves *b'' b'* to engage the edge of the fork. 60 The projecting portion *b'* of the bracket is provided with a vertical perforation, *b''*, Fig. 3, to receive the lantern-carrying rod *d*, adapted to allow said rod to be turned horizontally or be raised or lowered from the 65 ground, and with it the lantern, which is suspended from the lateral extension *d'*, as usual. Said arm is held to said bracket by a set-screw, *b'*, or similar device in any ordinary manner.

The device is secured to the fork by inserting the latter between the finger or turned end of the clip and grooved edge of the bracket, and then setting the clamping-screw to hold the parts rigidly together, as will be understood.

Having thus described the invention, what I claim as new is—

1. In combination, an adjustable clip, a bracket, and an adjustable lantern-rod depending from said bracket and provided with a lateral extension, *d'*, to receive the lantern, substantially as and for the purposes set forth.

2. In combination, an adjustable clip, a bracket having a grooved or recessed edge to engage the edge of the bicycle-fork, and a lantern-supporting rod adjustably held in said bracket, and adapted to be raised, lowered, or turned pivotally in said bracket, substantially as and for the purposes set forth.

3. In combination, a clip having a screw-shank, *c''*, a bracket having a groove or recess, *b''*, and perforations *b' b''*, a lantern-rod, and suitable nuts or screws to hold said parts in rigid relation, substantially as and for the purposes set forth.

4. In combination, a clip provided with a bent finger, *c''*, a bracket having a recessed or grooved edge, and a perforation to receive said clip, and having a vertical perforation to receive the lantern-arm and a suitable set-screw or fastener to secure said arm, all substantially as and for the purposes set forth.

5. In combination, a bracket provided with a lantern-support and a clip having an ad-

justable relation thereto, whereby the lantern
may be secured on either side or fork of the
bicycle without reversing the relation of the
lantern to said support or throwing the rays
5 of light therefrom in the reverse direction,
substantially as and for the purposes set forth.

In testimony that I claim the foregoing I

have hereunto set my hand this 29th day of
July, 1886.

WARREN LA FAYETTE FISH.
